US0D1075665S

(12) **United States Design Patent** (10) **Patent No.:** **US D1,075,665 S**
(45) **Date of Patent:** **** May 20, 2025**

(54) **WIRELESS CHARGER**

(71) Applicant: **Guanshui Nie**, Guangdong (CN)

(72) Inventor: **Guanshui Nie**, Guangdong (CN)

(**) Term: **15 Years**

(21) Appl. No.: **29/924,422**

(22) Filed: **Jan. 18, 2024**

(51) **LOC (15) Cl.** **13-02**

(52) **U.S. Cl.**

USPC **D13/108**

(58) **Field of Classification Search**

(57) **CLAIM**

The ornamental design for a wireless charger as shown and described.

DESCRIPTION

FIG. 1 is a perspective view of a wireless charger showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a perspective view of the wireless charger showing my new design in a closed position; and,

FIG. 10 is a perspective view of the wireless charger showing my new design in a closed position.

The broken lines depict portions of the wireless charger that form no part of the claimed design.

1 Claim, 10 Drawing Sheets
